UNITED STATES PATENT AND TRADEMARK OFFICE
CERTIFICATE OF CORRECTION

PATENT NO. : D652,176 S
APPLICATION NO. : 29/373294
DATED : January 10, 2012
INVENTOR(S) : Tom Bartak

Page 1 of 1

It is certified that error appears in the above-identified patent and that said Letters Patent is hereby corrected as shown below:

On the Title Page, Item (75)

Correct Name of Inventor is "TOM BARTAK." The last name of the inventor should be shown as "Bartak" and not "Tom."

Signed and Sealed this
Twenty-eighth Day of February, 2012

David J. Kappos
Director of the United States Patent and Trademark Office
